HEEL KNITTING MACHINE

Fritz Lambach, Fairview, N. J., assignor to Robert Reiner, Inc., Weehawken, N. J.

Application April 13, 1938, Serial No. 201,639

10 Claims. (Cl. 66—82)

The present invention relates to the manufacture of hosiery and, more particularly, to an improved flat or full-fashioned knitting machine of the type disclosed in my co-pending application, Serial Number 125,569, filed February 13, 1937, of which this application is a continuation in part. The machine to which the invention pertains is especially adapted to knit heel portions directly onto a combination full-fashioned foot and leg stocking blank in accordance with 10 the method disclosed in my co-pending application, Serial Number 110,707, filed November 13, 1936.

It is the principal object of the invention to provide mechanisms capable of knitting heel portions as continuations of the high heel sections of a combination foot and leg blank and, during the knitting of said heel portions, transfer certain loops of the sole sections of said blank for interlooping connection with loops at the inner selvedges of the heel portions, while transferring certain loops at the outer selvedges of the latter to narrow and shape the same.

It is also among the main objects of the invention to provide co-related mechanisms operable to knit heel portions as continuations of the high heel sections of a combination foot and leg blank, to transfer the marginal loops of the sole sections of said blank for overlapping, interlooping connection with certain loops at the inner selvedges of said heel portions, and to transfer certain loops at the outer selvedges of said heel portions to narrow and shape the same, said mechanisms being respectively associated to co-function in predetermined, timed relation.

Another important object of the invention resides in the provision of a mechanism adapted to knit heel portions into a combination foot and leg blank by knitting the heel portions directly onto the leg portion of the blank and, at the same time, interknit the inner selvedge edges of the heel portions into the adjoining portion of the foot fabric to form a finished blank.

In the manufacture of full-fashioned stockings of the so-called single unit type, it has been proposed to knit a combination foot and leg stocking blank in a continuous operation on one machine and, thereafter, on a separate machine, to knit the heel portions onto the blank in the form of heel flaps which are subsequently attached along their inner selvedge edges to the first course of the sole fabric by means of the usual looping operation.

The present invention aims to simplify this previously disclosed method by providing a ma-

chine devised to knit the heel portions into a combination stocking blank of the general description herein referred to, by a knitting operation in which the heel portions are knitted directly onto the leg portion of the blank and in which the inner selvedge edges of the heel portions, while being formed, are interknit with the adjoining portion of the foot fabric, thus eliminating the looping connection between the inner selvedge edges of the heel portions and the sole, thereby considerably reducing the amount of handling to which the blank is subjected, and the resulting cost of producing the stocking. The knitted connection thus formed between the heel portions and the sole fabric, consisting of interconnected overlapping loops, provides a strong and more flexible connection which is flat in appearance as compared with the present looping stitch.

The invention is moreover characterized by the fact that the mechanical realization thereof may be had through a novel combination of parts, easily and readily adaptable for association with an ordinary well-known footer knitting machine, without necessitating material changes in the basic construction and operation thereof.

It is also a characteristic feature of the invention to provide a simplified attachment which may be conveniently and easily combined with a standard footer knitting machine for converting the same into a heeling machine.

With these and other objects in view, as may hereinafter appear, the several features of the invention and the advantages to be obtained thereby will be readily understood by one skilled in the art from the following description, taken in conjunction with the accompanying drawings, in which:

Figure 1 is a front elevation of a portion of a knitting machine embodying the invention.

Figure 2 is a transversal section taken through lines 2—2 of Figure 1, showing on a reduced scale the elements illustrated in Figure 1 associated with certain parts and operable elements of the knitting machine.

Figure 3 is an enlarged cross section taken on line 3—3 of Figure 2.

Figure 4 is a side elevation of the parts shown in Figure 3 with certain portions in section.

Figure 5 diagrammatically illustrates a combination full-fashioned stocking blank in which the foot portion is knitted directly onto the leg and high heel portions thereof.

Figure 6 is a diagrammatic illustration, on an enlarged scale, of the blank shown in Figure 5 at

the juncture of a high-heel portion and a sole portion, topped on two series of topping points in paralleling relationship.

Figure 7 diagrammatically shows the last course of a high heel portion and the first course of a sole portion topped onto the two series of topping points in straight line relationship subsequent to the serving of the blank at the juncture of said high heel and sole portions for engagement with the transfer bar.

Figure 8 is a face elevation of a knitting section of the heeling machine with portions broken away.

Figure 9 is a detail sectional view in side elevation showing a portion of the heeling machine and transfer bar for the transfer of the fabric from the transfer bar to the heeling machine.

Figure 10 diagrammatically represents the relative positioning of the high heel, sole, and heel portions of the stocking blank after knitting a number of heel courses.

Figure 11 is a face elevation illustrating the complete foot and leg stocking blank with the heel portions knitted therein.

Having more particular reference to the drawings, wherein like characters of reference will designate corresponding parts throughout, it is to be understood that I have shown only those parts of a full-fashioned hosiery knitting machine which are essential to a clear understanding of the present invention, the basic structure of the knitting machine itself being that of the commonly used footer with which anyone skilled in the art is well acquainted.

In the drawings illustrating the preferred construction of the improved knitting machine, the usual machine frame is indicated at 10 and carries a center bed 12 about which are mounted a plurality of spaced knitting sections, designated in their entirety by the reference character 14.

Each knitting section 14 essentially comprises a needle bar 16, knockover bits 18, and sinkers and dividers 20. The thread or yarn is fed to the knitting sections 14 by means of the carriers 22 depending from the carrier rods 24 mounted for reciprocation in the carrier rod brackets 26. The relative position, essential operation, and function of the needle bar, knockover bits, sinkers, dividers, and carriers are well known by those skilled in the art and, therefore, need not be described in detail herein.

The needle bar 16 carries the knitting needles 28, certain of which are adapted to receive yarn from the carriers 22 and act to knit fabric, the remaining needles being inactive and serving only to retain the loops of a previously knitted fabric for the purpose to be explained in detail hereinafter.

Disposed for cooperation with a predetermined number of active needles at the opposite ends of the needle bar are two relatively small narrowing combs 30 and 32 (Figure 1), respectively fixed to separate narrowing bars 34 and 36 slidably mounted in the usual brackets 37, whereas arranged for coaction with the inactive needles are two relatively wide loop transfer combs 38 and 40 likewise respectively secured to separate narrowing bars 42 and 44, which are also slidably mounted in said brackets 37.

The narrowing combs 30 and 32 are intended to operate independently of the loop transfer combs 38 and 40 and, for that purpose, two separate and distinct mechanisms are utilized. One mechanism, which may be the usual well known

narrowing mechanism, is operatively associated with the narrowing bars 34 and 36 to impart a longitudinally sliding movement thereto, while the other mechanism, which may be a loop transfer control mechanism of the type shown and described in my prior Patent No. 2,002,116, dated May 21, 1935, is associated with the bars 42 and 44 to impart a longitudinally reciprocating movement thereto.

As more clearly shown in Figure 1, the narrowing mechanism comprises a pair of narrowing nuts 46 and 48 respectively engaged with a double threaded spindle 50 rotatably carried in the brackets 37 so that, upon rotation of said spindle, the narrowing nuts will travel in opposite directions, as indicated by the arrows A and B. The narrowing nuts are provided with sleeves 52 and 54 slidable on the narrowing shaft 56 supported by the brackets 37. The sleeve 52 of the narrowing nut 46 is provided with a flange 58 connected to the narrowing bar 34 as indicated at 60, and the sleeve 54 of the narrowing nut 48 also has a flange 62 connected to the narrowing bar 36, as shown at 64. In this manner, it will be understood that said narrowing bars 34 and 36 with their reciprocating narrowing combs 30 and 32 will follow the movement of the corresponding narrowing nuts when the spindle 50 is rotated during a narrowing cycle of the knitting machine.

During such a cycle, the rotation of the spindle 50 is accomplished automatically, through actuation of a pawl and ratchet device 66 operated in the usual manner well known in the art. The narrowing machine may be reset through the ordinary crank and gear mechanism 67.

As shown in the various Figures 1 to 4 inclusive, the loop transfer control mechanism comprises a shaft 68 suitably fixed in bearings 70 arranged upon adjacent brackets 37.

Freely mounted on said shaft 68 is a rotatable member 72 formed with ratchet teeth 74 engaged by a pawl 76 which is pivoted at 78 to an arm 80 freely mounted on the rotatable member 72. A spring 82 urges the pawl towards the ratchet teeth. The pawl is flattened as at 76a and 76b and when in engagement with the ratchet teeth, the spring 82 engages the face 76a. When thrown out of engagement with the teeth, the spring then engages the face 76b. Pivoted, as at 84, in the arm 80 is an operating connection 86. As this operating connection is raised, or the narrowing mechanism is lowered, the pawl will be retracted to engage another tooth of the ratchet, and when the operating connection is lowered, or the narrowing mechanism raised, the pawl will move the rotatable member in relation to the shaft 68.

The operating connection 86, at its lower extremity, is pivoted to a lever 88 which, in turn, is pivoted at 90 to a suitable part of the knitting machine frame. The lever 88 carries a cam roller 92 which engages a cam 94 fixed to the cam shaft 96. A spring 98 maintains the cam roller 92 in engagement with the cam 94. A flexible connection 100 is interposed on the operating connection 86.

To prevent the rotatable member from overrunning, and to insure its position on the shaft 68, said member is provided with a series of notches 102 which are engaged by a spring-pressed plunger 104. The plunger 104 is mounted in ears 106 formed on a bracket 108 suitably secured to the narrowing shaft 56. A spring 110 is interposed between the uppermost ear 106 and

a collar 112 on the plunger. The plunger may be raised by a handle 114 when it is desired to relieve the spring to move the rotatable member by hand.

The rotatable member 72 is provided with a hub or boss 116 having on its face alternating raised portions 118 and recessed portions 120. Secured by means of a pin 122, or like element, to the shaft 68 adjacent the rotatable member 72 is a rectangular block 124. Suitably arranged for sliding movement upon two diametrically opposed faces of said block, are plates 126 and 128, each provided on one side with a flange 130 and on one end with a nose 132 disposed for engagement with the raised and recessed portions 118 and 120 of the rotatable member 72.

The flange of the plate 126 is rigidly connected to the narrowing bar 42 carrying the loop transfer comb 38, whereas the flange of the plate 128 is rigidly connected to the narrowing bar 44 carrying the loop transfer comb 40, for instance, as indicated at 134 and 136 respectively.

Constant engagement of the noses 132 with the cooperating face of the rotatable member 72 is assured by means of springs 138 normally urging the narrowing bars in a direction towards said member. The relative position of the raised and recessed portions 118 and 120 on the rotatable member 72 is such that when the nose of one plate 126 or 128 engages a raised portion, the nose of the other plate engages a recessed portion. Thus, during rotation of said member 72, the plates 126 and 128 are caused to slide in opposite directions, thereby imparting opposed reciprocating movements to the narrowing bars 42 and 44 as indicated by the arrows C and D (Figure 1).

Moreover, the relative height and depth of said raised and recessed portions are predetermined so as to cause the combs 38 and 40 to move over the desired or required number of needles to correspondingly affect the transfer of the loops.

From the foregoing description of the loop transfer mechanism, it will be understood that, upon rotation of the main cam shaft 96 during a loop transfer cycle, the narrowing mechanism will be caused to dip rapidly in the usual manner to bring the transfer points into engagement with the needles to engage the loops thereon. At the same time, due to the contour of the cam 94, the operating connection 86 will be slightly lowered, but at a slower speed than the narrowing mechanism so that the pawl 76 will be retracted to engage a new tooth of the ratchet 94. The narrowing mechanism is then moved upwardly with the continued rotation of the cam shaft 96 to pick up or lift the loops off the needles 28 and to bring the points above the line of the sinkers and dividers 20. As the points are raised above the sinker and divider level, the operating connection 86 is moved downwardly by the operation of the arm 88 and operates to rotate the ratchet 74 and rotatable member 72 to shift the narrowing bars 42 and 44 laterally and index the points of the loop transfer combs 38 and 40 with another set of needles. The narrowing mechanism is again depressed to engage the transfer points and loops held thereon with the needles and is finally returned to its neutral position, leaving the loops on the needles.

During the second downward movement of the narrowing mechanism, the pawl 76 is again retracted in relation to the ratchet 74, this movement being caused by the downward movement

of the narrowing mechanism, while at the same time, the operating connection 86 is carried upwardly by the rise of the arm 88 on the cam 94. During the final upward movement of the narrowing mechanism to its raised position, the narrowing mechanism frame moves upwardly with relation to the operating connection 86 so that the pawl 76 is again actuated to rotate the ratchet 74, and the rotatable member 72, to again index the transfer points laterally with relation to the needles preparatory to the beginning of another loop transferring operation.

Attention is called to the fact that the narrowing mechanism and loop transfer mechanism may operate conjointly with, or independently of, each other. With the ratchet device 66 and the pawl and ratchet arrangement 74-76 in the relative position more clearly shown in Figure 1, it will be understood that both the narrowing mechanism and the loop transfer mechanism will operate in unison. However, by disengaging the pawl 76 from the ratchet 74, the loop transfer mechanism may be rendered inactive without affecting the operation of the narrowing mechanism, but by disrupting the action of the ratchet device 66, the narrowing mechanism will cease to function while the loop transfer mechanism continues to operate.

As hereinbefore stated, the machine is devised to knit heel portions onto a combination full-fashioned leg and foot blank of the type represented in Figure 5. As shown in said Figure 5, the blank 130 comprises a leg 132 having reinforced high heel portions 134 and a foot 136 with reinforced sole portions 138 which are formed by continuous knitting into the combination foot and leg blank.

Between the leg and foot portions of the blank, as best shown in Figure 6, two partial non-reinforced courses 140 are provided which serve to form a line of demarcation between those portions of the last course of the foot fabric and the first course of the sole fabric into which the heel portions are subsequently to be knitted. During the knitting of the partial courses above referred to, the knitting with the reinforced yarn is continued on a restricted number of needles so that a reinforced selvedge loop 142 is provided at the inner ends of the partial non-reinforced connecting courses 140 to form the heel corner of the finished blank.

It will be understood that the courses 140 may be knitted with a separate yarn so that when these connecting loops are subsequently removed, as by cutting or pulling out the yarn forming these loops, to separate the reinforced high heel and sole portions of the blank, no yarn forming the body portion of the fabric will have been broken or cut.

In accordance with the invention, the last course of the leg fabric loops designated at 144 and the first course of reinforced sole fabric loops designated at 146, together with the selvedge loop 142, are topped onto a series of topping points comprising a stationary point 148 and two additional point sections designated respectively at 150 and 152 which are arranged in parallel relationship, as shown in the diagrammatic Figure 6, that is, in substantially the same positions in which the fabric loops appear in the combination blank.

It will be noted that the topping operation, as described, is carried out prior to the cutting or removal of the partial non-reinforced courses 140 so that when the high heel and sole por-

tions of the fabric are separated, all of the disengaged fabric loops are supported by the topping points to prevent any possibility of dropping these loops.

In accordance with the preferred form of applicant's method, the loops forming the partial courses 140 may be severed by means of a cutting knife 154 to permit the separation of the two parallel topping point sections and the loops supported thereon which are then moved outwardly into a straight line relationship (Figure 7), in which all of the points are spaced to register with the quills of a transfer bar which may be of ordinary description, and so utilized for transferring the fabric loops from the topping points to the needles of the heel machine.

The construction and operation of the topping stand per se which is disclosed in my copending application, Serial Number 125,569, filed February 13, 1937, forms no part of this invention and, therefore, need not be described herein.

The steps of transferring the fabric from the transfer bar to the needles of a machine for knitting the heel portions may be briefly described in connection with Figure 9. As shown, the transfer bar 156 is placed in supporting brackets 158 formed on each end of the needle bar in which pins 160 on said transfer bar engaged within the slots 162 formed in the brackets 158 to register the quills 155 with the needles 28. The needles 28 may then be moved rearwardly and upwardly, the sinkers and dividers 20 at the same time being advanced so that the fabric is engaged thereby and forced from the quills onto the shank of the needles. The transfer bar may then be removed from the needles to permit the knitting of the heel portions.

In knitting the heel portions, the carriers 22 are actuated in the well known fashion to lay the yarn or yarns across the active knitting needles so as to knit the courses 164 (Figure 10) of the heel portions 166. During the knitting of said heel portions, the loops 146 of the first course of the sole portion 138 are gradually transferred for interknitted engagement with said fabric by operation of the loop transfer mechanism already described.

The heel portions 166 may be shaped in the usual manner, as indicated at 168, through operation of the narrowing mechanism functioning to actuate the narrowing combs 30 and 32, as previously explained.

The invention having been described, what I claim is:

1. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses: a needle bar having a set of knitting needles for each of said leg fabric portions and adapted to knit heel tab courses into the latter, and a set of non-knitting needles for each of said foot fabric portions and adapted to support a course of loops thereof; loop transfer combs one for each set of non-knitting needles, adapted to engage and successively transfer the loops supported on the latter onto certain of the knitting needles for interknitting the transferred loops with certain of the loops of the courses knitted thereby; transfer bars, one for each transfer comb, each transfer bar carrying its transfer comb and movable to impart individual movement to the latter longitudinally of the needle bar.

5 on the needle bar; and a single progressively rotatable member common to said transfer bars and associated therewith whereby, through the progressive rotation of said member, to impart to the transfer combs relative back and forth movements in opposite directions longitudinally of the needle bar.

2. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses: a needle bar having 10 a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; transfer bars, one 15 for each transfer comb, each transfer bar carrying its transfer comb and movable to impart individual movement to the latter longitudinally on the needle bar; a single progressively rotatable member common to said transfer bars and associated therewith whereby, through the progressive rotation of said member, to impart to the transfer combs relative back and forth movements in opposite directions longitudinally of the needle bar; and a pawl and ratchet device connected to said member and operatively associated with the knitting machine to be actuated thereby for rotating said member step by step during the function of the machine.

3. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses: a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; transfer bars, one for each transfer comb, each transfer bar carrying its transfer comb and movable to impart individual movement to the latter longitudinally on the needle bar; a single progressively rotatable member common to said transfer bars; yieldable means associated with the transfer bars to normally urge the same towards said member; and said member having an alternating arrangement of projections and depressions disposed to act on the transfer bars alternatively in cooperation with said yieldable means whereby, through the progressive rotation of said member, to impart to the transfer combs relative back and forth movements in opposite directions longitudinally of the needle bar.

4. In a knitting machine for forming heel tabs between leg and foot fabric portions of a combination stocking blank by knitting the heel tabs

as continuations of the leg fabric portions and transferring loops of the foot fabric portions for interknitting with loops of said heel tabs as the knitting thereof progresses: a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; transfer bars, one for each transfer comb, each transfer bar carrying its transfer comb and movable to impart individual movement to the latter longitudinally on the needle bar; a single progressively rotatable member common to said transfer bars; yieldable means associated with the transfer bars to normally urge the same towards said member; said member having an alternating arrangement of projections and depressions disposed to act on the transfer bars alternatively in cooperation with said yieldable means whereby, through the progressive rotation of said member, to impart to the transfer combs relative back and forth movements in opposite directions longitudinally of the needle bar; and a pawl and ratchet device connected to said member and operatively associated with the knitting machine to be actuated thereby for rotating said member step by step during the function of the machine.

5. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses: a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; transfer bars, one for each transfer comb, each transfer bar carrying its transfer comb and movable to impart individual movement to the latter longitudinally on the needle bar; a single progressively rotatable member common to said transfer bars; extensions connected to the transfer bars and projecting therefrom to lie in line with said member; yieldable means associated with the transfer bars to normally urge the extensions thereof into bearing engagement with said member; said member having an alternating arrangement of projections and depressions adapted to contact said extensions of the transfer bars and so disposed that when the extension of one transfer bar engages a projection, the extension of the other transfer bar engages a depression whereby, through the progressive rotation of said member, to impart to the transfer combs relative back and forth movements in opposite directions longitudinally of the needle bar.

6. In a knitting machine for forming heel tabs between leg and foot fabric portions of a combination stocking blank by knitting the heel tabs

as continuations of the leg fabric portions and transferring loops of the foot fabric portions for interknitting with loops of said heel tabs as the knitting thereof progresses: a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; transfer bars, one for each transfer comb, each transfer bar carrying its transfer comb and movable to impart individual movement to the latter longitudinally on the needle bar; a single progressively rotatable member common to said transfer bars; extensions connected to the transfer bars and projecting therefrom to lie in line with said member; yieldable means associated with the transfer bars to normally urge the extensions thereof into bearing engagement with said member; said member having an alternating arrangement of projections and depressions adapted to contact said extensions of the transfer bars and so disposed that when the extension of one transfer bar engages a projection, the extension of the other transfer bar engages a depression whereby, through the progressive rotation of said member, to impart to the transfer combs relative back and forth movements in opposite directions longitudinally of the needle bar; and a pawl and ratchet device connected to said member and operatively associated with the knitting machine to be actuated thereby for rotating said member step by step during the function of the machine.

7. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses, the combination with a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; and transfer bars, one for each transfer comb, each transfer bar carrying its transfer comb and movable to impart individual movement to the latter longitudinally on the needle bar of: a mechanism for moving said transfer bars and comprising a stub shaft supported in a plane extending longitudinally of the transfer bars; a member mounted on said shaft to rotate in a plane transversely of the transfer bars, one face of said member having an annular arrangement of alternating projections and depressions; a block fixed on said shaft; a pair of plates slideable in said block axially of said member and so disposed in relation to the latter that one plate is aligned with a projection while the other plate is aligned with a depression; means for connecting one plate to one transfer bar; means

for connecting the other plate to the other transfer bar; yieldable means acting to urge said plates in bearing engagement with said member; and means functioning to impart a step by step rotation to said member whereby the projections and depressions thereof in cooperation with said yieldable means displace the transfer bars to impart relative movement to the transfer combs in opposite directions longitudinally of the needle bar.

8. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses, the combination with a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; and transfer bars, one for each transfer comb, each transfer bar carrying its transfer comb and movable to impart individual movement to the latter longitudinally on the needle bar of: a mechanism for moving the transfer bars and comprising a stub shaft supported in a plane extending longitudinally of the transfer bars; a member mounted on said shaft to rotate in a plane transversely of the transfer bars, one face of said member having an annular arrangement of alternating projections and depressions; a block fixed on said shaft; a pair of plates slideable in said block axially of said member and so disposed in relation to the latter that one plate is aligned with a projection while the other plate is aligned with a depression; means for connecting one plate to one transfer bar; means for connecting the other plate to the other transfer bar; yieldable means acting to urge said plates in bearing engagement with said member; and a pawl and ratchet functioning to impart a step by step rotation to said member whereby the projections and depressions thereof in cooperation with said yieldable means displace the transfer bars to impart relative movement to the transfer combs in opposite directions longitudinally of the needle bar.

9. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses, the combination with a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops support-

ed on the latter onto certain of the knitting needles for interknitting the transferred loops with certain of the loops of the courses knitted thereby; and transfer bars, one for each transfer comb, each transfer bar carrying its transfer comb and movable to impart individual movement to the latter longitudinally on the needle bar, of: a mechanism for moving the transfer bars and comprising a member mounted to rotate in a plane transversely of the transfer bars, one face of said member having an annular arrangement of alternating projections and depressions; a pair of plates slideable axially of said member and so disposed in relation to the latter that one plate is aligned with a projection while the other plate is aligned with a depression; means for connecting one plate to one transfer bar; means for connecting the other plate to the other transfer bar; yieldable means acting to urge said plate in bearing engagement with said member; and means functioning to impart a step by step rotation to said member whereby the projections and depressions thereof, in cooperation with said yieldable means, displace the transfer bar to impart relative movement to the transfer combs in opposite directions longitudinally of the needle bar.

10. In a knitting machine for forming heel tabs between leg and foot fabric portions of a combination stocking blank by knitting the heel tabs as continuations of the leg fabric portions and transferring loops of the foot fabric portions for interknitting with loops of said heel tabs as the knitting thereof progresses, the combination with a needle bar having a set of knitting needles for each of said leg fabric portions and adapted to knit heel tab courses into the latter, and a set of non-knitting needles for each of said foot fabric portions and adapted to support a course of loops thereof; loop transfer combs, one for each set of non-knitting needles, adapted to engage and successively transfer the loops supported on the latter onto certain of the knitting needles for interknitting the transferred loops with certain of the loops of the courses knitted thereby; and transfer bars, one for each transfer comb, each transfer bar carrying its transfer comb and movable to impart individual movement to the latter longitudinally on the needle bar, of: a mechanism for moving the transfer bars and comprising a member mounted to rotate in a plane transversely of the transfer bars, one face of said member having an annular arrangement of alternating projections and depressions; a pair of plates slideable axially of said member and so disposed in relation to the latter that one plate is aligned with a projection while the other plate is aligned with a depression; means for connecting one plate to one transfer bar; means for connecting the other plate to the other transfer bar; yieldable means acting to urge said plate in bearing engagement with said member; and a pawl and ratchet device functioning to impart a step by step rotation to said member whereby the projections and depressions thereof, in cooperation with said yieldable means, displace the transfer bars to impart relative movement to the transfer combs in opposite directions longitudinally of the needle bar.

FRITZ LAMBACH.
